(57) **CLAIM**

The ornamental design for an electronic cigarette atomizer as shown and described.

DESCRIPTION

The patent or application file contains at least one drawing executed in color. Copies of this patent or patent application publication with color drawing(s) will be provided by the Office upon request and payment of the necessary fee.

2.6: Right

2.7: Top

2.8: Bottom

The present design relates to an electronic cigarette atomizer; reproductions **1.1** to **1.8** are respectively a top perspective, a bottom perspective, front, rear, left side, right side, top, and bottom view of an embodiment of the electronic cigarette of the present design; and reproductions **2.1** to **2.8** are respectively a top perspective, a bottom perspective, front, rear, left side, right side, top, and bottom view of another embodiment of the electronic cigarette of the present design.

In **1.1-1.8** the dashed broken lines depict portions of the electronic cigarette atomizer that form no part of the claimed design. In **2.1-2.8**, the dashed broken line depicts a boundary and the portion within, deemphasized under transparent gray

(Continued)

shading, depict portions of the electronic cigarette atomizer that form no part of the claimed design.
